INVENTOR,

Bernando S. Smith.

UNITED STATES PATENT OFFICE.

BERNANDO S. SMITH, OF PROVIDENCE, RHODE ISLAND, ASSIGNOR TO
SARAH L. SMITH, OF SAME PLACE.

IMPROVEMENT IN CORSETS.

Specification forming part of Letters Patent No. 179,968, dated July 18, 1876; application filed
March 16, 1876.

To all whom it may concern:

Be it known that I, BERNANDO S. SMITH, of the city and county of Providence, in the State of Rhode Island, have invented a new and Improved Combined Corset and Skirt-Supporter; and declare the following to be a specification thereof.

In the accompanying drawings like letters indicate like parts.

Figure 1 is a perspective view of the front of my invention. Fig. 2 is a perspective view of the back of the same. Figs. 3, 4, and 5 are detail views.

My invention consists in combining with a corset adjustable shoulder-straps, terminating with a hook or pin, by which the skirts are supported; and, also, in strengthening and protecting the corset steels or clasps by fastening to the under one a broader piece of metal to resist strain or pressure.

The corset A may be made in any of the shapes commonly known, and is provided with straps B, passing over the shoulders, and which are connected on the back by the cross-piece a, to prevent them from slipping from the shoulders. The straps B pass through the slides C, and form a loop by means of the buckles D. By sliding this buckle upon the strap B this loop is made longer or shorter, as may be desired, and so the straps B are adjusted to any desired length. Through the rings of the slides C pass the front straps E, for supporting the skirt. One end, b, of each of these front straps is permanently fastened to the corset A. The other end of each front strap, as also the ends of the straps B upon the back of the corset, terminate with a hook, F. The straps B and E pass between the exterior of the corset and its lining, and through the apertures c to the outside. A free vertical motion of these straps within the corset can thus be had, enabling the proper adjustment of the skirt-supporter.

The hook F consists of a sharp-pointed spring-wire, bent as fully shown in Fig. 3. It is secured to a loop at the end of the strap B or E, and has a coil or twist, d, to give elasticity to the tongue e. A guard, f, fastens the tongue in place, and covers its sharp point.

(See Fig. 3.) The tongue is unsprung from the guard, and is thrust through the waistbands of the skirts, and is then sprung within the guard again, so holding the skirts securely.

It is obvious that, instead of this arrangement of the hook and pin, a hook and eye, or button and loop, or other similar contrivance, would be useful.

This skirt-supporting device may be used, also, in connection with a waist instead of a corset, but would obviously, as thus used, be within my invention.

Fig. 4 shows the clasps G G' of the corset, which are fastened together in the usual manner when worn; but I strengthen the clasp G by a clasp-protector, H, consisting of a piece of steel, or other suitable metal, of the same shape as the clasp G, but made broader, and thus affording a support for both the clasps. The pieces G and H are fastened together as shown in Fig. 5. The protector H, near its ends, is cut half-way across, and the narrow end piece so cut is folded over upon the clasp G, and holds it and piece H firmly to each other. Midway at intervals may be one or more projecting pieces, g, of the protector H, folded back upon the clasp G in a similar manner.

The purpose of this protector is to prevent the breakage which frequently results from the bending of the body, and also to strengthen the clasps G G' in position.

I therefore claim as a novel and useful invention, and desire to secure by Letters Patent—

1. The shoulder-straps B, adjustable by means of the slides C, buckles D, and straps E, and provided with skirt-supporting hooks or pins F, in combination with a corset, A, and applied thereto, substantially as and for the purpose specified.

2. The clasp-protector H, in combination with the clasp G, fastened thereto substantially as specified, and used for the purposes described.

BERNANDO S. SMITH.
